UNITED STATES PATENT OFFICE.

ARCHIBALD JAMES MACDOUGALL AND GUY NOVERRE MIDDLETON, OF TORONTO,
ONTARIO, CANADA, ASSIGNEES TO THE TORONTO POWER COMPANY, LIMITED,
OF TORONTO, ONTARIO, CANADA, A CORPORATION OF ONTARIO.

ELECTROLYTIC APPARATUS.

1,269,566.

Specification of Letters Patent. Patented June 11, 1918.

Application filed July 5, 1917. Serial No. 178,616.

To all whom it may concern:

Be it known that we, ARCHIBALD JAMES MACDOUGALL and GUY NOVERRE MIDDLETON, both subjects of the King of Great Britain, residing at the city of Toronto, in the county of York and Province of Ontario, Dominion of Canada, have invented certain new and useful Improvements in Electrolytic Apparatus; and we hereby declare that the following is a full, clear, and exact description of the same.

This invention relates to an electrolytic apparatus, containing certain novel features of construction which contribute to its electrolytic efficiency; (a) by continually changing the electrolyte in the zone of action and thereby maintaining a constant supply of fresh electrolyte at the active electrode surfaces; (b) by causing a continual movement of the electrolytic products from the zone of action and thereby preventing a stagnant condition of the gaseous and liquid products, and an accumulation of solid products, at the active electrode surfaces; (c) by keeping the zone of action free from an accumulation of gaseous products and thereby preventing an appreciable increase of resistance in the electrolyte path of the current from one electrode to the other; (d) by returning the electrolyte during its cycle of action through separating tanks interposed in its circulation between the offtakes and the intakes, and providing heat exchangers to maintain a desired temperature of the electrolyte and thereby accelerate the electrolytic reaction; and (e) by providing insulated offtakes of appropriate cross-sectional area and length to permit of a sufficient accumulation of gases in the electrolyte therein to offer an effective resistance to the flow of the current through the electrolyte and thereby reduce the shunt current losses to a negligible quantity.

In the drawings:—

- 45 Figure 1, is an irregular side sectional elevation of the preferred type of apparatus;
Fig. 2, is an end sectional elevation of the apparatus shown in Fig. 1;
50 Fig. 3, is a vertical section and Fig. 3^a, is a horizontal section, of a battery of cells

similar to those shown in Figs. 1 and 2, but on a larger scale;

Fig. 4, is a side sectional elevation of a modified form of the apparatus shown in Figs. 1, 2 and 3;

Fig. 5, is an end sectional elevation of the apparatus shown in Fig. 4; and,

Fig. 6 is a fragmentary detail view of the preferred type of electrode. 60

The apparatus, which may contain one cell, or any multiple number of cells, is shown in Figs. 1 to 3 inclusive, as comprising a battery of six cells, numbered 1 to 6 inclusive, with a reacting couple suspended 65 interjacent the walls *f* of each cell structure, each reacting couple consisting of two perforate or permeable electrodes *a* and *b*, with a diaphragm *c* between them, the construction of the electrodes and their arrangement in the cells being such as to permit of the free circulation of the electrolyte and the electrolytic products lengthwise and transversely of the reacting couple. 70

In the preferred type, as shown in Fig. 6, 75 each electrode is composed of two suitably-spaced distributor bars *a'*, *b'*, and a multiplicity of reacting structures *c'* assembled on the distributor bars. These reacting structures constitute the current conducting 80 paths, and take the form of conducting strips projecting into and through the electrolyte, contained by the reacting couple, to shorten the electrolyte path of the current from one electrode to the other, with spacings *c''* between the reacting structures *c'* to provide lengthwise and transverse paths through the electrode for the circulation of the electrolyte and the electrolytic products lengthwise and transversely of the reacting couple. 85

A convenient means for suspending the reacting couple within the cell, as shown in Figs. 1, 2 and 3, is to provide the electrode *a* with arms *d* and the electrode *b* with 90 similar arms *e*, bolted, riveted, welded, or otherwise secured to the electrode and to the walls of the cell structure, these arms holding the electrodes rigidly in their fixed relation to each other to constitute the reacting couple, and in their set position interjacent the walls of the cell structure to per- 100

mit of the electrodes being surrounded by electrolyte.

This suspension, together with the perforate or permeable character of the electrodes, 5 provides for the free circulation of the electrolyte lengthwise and transversely of the electrodes, this circulation contributing to the efficiency of the electrolytic reaction: (a) by continuously changing the electrolyte 10 in the zone of action, and thereby maintaining a constant supply of fresh electrolyte at the active electrode surfaces; (b) by causing a continual movement of the electrolytic products from the zone of action, 15 and thereby preventing a stagnant condition of gaseous and liquid products and an accumulation of solid products at the active electrode surfaces; and (c) by keeping the zone of action free from an accumulation of 20 gaseous products, and thereby preventing any appreciable increase of resistance in the electrolyte path of the current from one electrode to the other.

The walls *f* of the cell structure are preferably of the filter-press type, and each diaphragm *c*, when the walls of its respective cell structure are assembled, is clamped between them to separate the cell into two compartments *g*, *g'*, and to insulate these 30 compartments one from the other, the electrode *a* being contained in the compartment *g* and the electrode *b* being contained in the compartment *g'*.

If the walls of the cell structure are of 35 conducting material, the current may circuit, by means of the walls and the arms and electrode couples, but if the walls of the cell structure are of non-conducting material, the bolts or rivets *h*, *h'* securing the 40 arms of the terminal electrodes to the exterior walls of the terminal cells 1 and 6, may be extended beyond the walls *f*, and electrical conductors *i*, *i'* may be connected to them, the arms of the intermediate electrodes being electrically connected by bolts *h''*, as shown in Fig. 3.

In either case, the current circuits, by means of the arms *d* of the terminal electrode *a* in cell 1, its reacting electrode *b*, 50 and arms *e*, to the arms *d* of the electrode couple in cell 2, and so on throughout the battery of cells to the arm *e* of the terminal electrode *b* in cell 6.

At the top of each compartment *g*, *g'* is 55 an outlet *j*, *j'* for the electrolytic products, and each of these outlets *j*, *j'* is provided with an insulated tube *k*, *k'*, respectively, preferably glass. At the upper ends of the tubes *k*, *k'* are manifolds *l*, *l'* connected 60 by insulated tubes or couplings *m*, *m'*, preferably glass, with the headers *o*, *o'*. The outlet *j*, tube *k*, manifold *l*, tube *m*, and header *o*, may constitute the offtake for the products of the anolytic action, and the out-

let *j'*, tube *k'*, manifold *l'*, tube *m'* and header *o'* may constitute the offtake for the products of the catholytic action, these products being kept separate in the cell by the presence of the diaphragm between the anode and the cathode, this diaphragm, in 70 the preferred form of apparatus, being extended beyond the reacting couple and clamped between the two parts of the cell structure.

By making the tubes *k*, *k'* and *m*, *m'* 75 of glass, the manifolds *l*, *l'* and the headers *o*, *o'* may be effectively insulated from the cell structure, and by making the tubes *k*, *k'*, and *m*, *m'* of a cross-section and length of suitable proportional ratio the evolved 80 gases which accumulate in the upper part of the cell from the electrolytic decomposition will successively carry through the tubes or offtake portions of the electrolyte. These successive alternations of gas and electrolyte prevent the formation of shunt circuits through the medium of the continuous column that would otherwise exist in the interior of these offtakes, and by so disrupting the liquid column prevent the occurrence of shunt current losses and the formation of undesirable electrolytic products. The lifting effect of the gas columns due to 85 their being of lesser mass than an equivalent volume of liquid causes an automatic 90 circulation of the electrolyte from the cell through the offtake tubes and through the headers *o*, *o'* to the separating tanks *y*, *y'* and from thence through the return headers *p*, *p'*, and insulated intakes to the bottom 95 of the cell. This automatic circulation is most essential as by means of it the deionization of the electrolyte is prevented in the anodic and cathodic chambers of the cell, which would otherwise result, due to the 100 continuous passage of the electrolyzing current, in the ohmic resistance of the electrolyte being materially increased with a consequent reduction in the efficiency of the 105 operation of the cell.

At the bottom of the cells are intake headers *p*, *p'*, connected by insulated tubes *q*, *q'*, 110 preferably glass, with the compartments *g*, *g'*, respectively, for the inflow of electrolyte to the cells, the purpose of the tubes *q*, *q'* being to insulate the cells from the headers *p*, *p'*.

The outer walls of the terminal cells 1 and 6 may be provided with apertured lugs *r*, through which pass insulated coupling 120 bolts *s*, these bolts maintaining the assembly of the cells, and connected with the exterior walls of the terminal cells are casters *t*, *t'*, of conducting metal, traveling on conducting rails *u*, *u'*, which are insulated from 125 ground by suitable insulators *o*, preferably asbestos and porcelain, the current conductors *w*, *w'* being connected to the rails *u*, *u'*.

when the walls of the cell structures are of conducting material.

In the operation of the apparatus shown in Figs. 1, 2 and 3, the current circuits, by means of the conductor *w*, rail *u*, caster *t*, exterior wall of terminal cell 1, arms *d*, electrode *a*, electrode *b*, arms *e*, to the interior wall of the cell 1, and arms *d* of the electrode *a* of the reacting couple of cell 2, and so on throughout the battery, to the exterior wall of terminal cell 6, casters *t'*, conducting rail *u'* and conductor *w'*.

During this circuit of the current, the electrolyte is decomposed at the active surfaces of the reacting couple, this decomposition setting up a state of motion which causes the electrolyte and the electrolytic products to circulate freely in the zone of action lengthwise and transversely of the reacting structures, the gaseous products ascending in their respective compartments *g*, *g'* to the outlets *j*, *j'*, through which they pass to the insulated tubes *k*, *k'*, manifolds *l*, *l'*, tubes *m*, *m'* and headers *o*, *o'* to the separating tanks *y*, *y'* in which the electrolyte, carried with the gases to the tanks *y*, *y'*, is separated from the gases and returned through the return pipes *x''*, *x'* to the intake headers *p*, *p'*, through which it again feeds into the compartments *g*, *g'*, the separating tanks being provided with heat exchangers *x* to increase or decrease the temperature of the electrolyte and thus restore it to the desired temperature at which the electrolytic action may be carried on with the greatest efficiency.

In Figs. 4 and 5, the electrodes of the reacting couple may be similarly constructed to those used in the apparatus shown in Figs. 1, 2, and 3, and shown in detail in Fig. 6, but instead of suspending the reacting couple within the cell structure by means of conducting arms, the distributor bars may be connected by appropriate bolts 10 directly to the walls of the cell structures, the bolts being preferably such as to permit of the lateral adjustment of the electrodes to each other, or other appropriate means, within the scope of the appended claims, may be provided for holding each reacting couple in a set position within the cell to permit of the circulation of the electrolyte.

In Figs. 4 and 5, each cell is provided with two manifold sections 11 and 11^a, the manifold sections of one cell corresponding in dimensions and location with those of the other cells, so that when the cells are assembled, these sections will constitute continuous manifolds extending lengthwise of the group or battery of cells for the anolytic and catholytic products respectively, these manifolds being provided with insulated tubes 12, 12^a leading to headers 13, 13^a, the insulated tubes being for the same purpose,

and similar in all respects to the insulated tubes *k*, *k'*.

While the same circulation of the electrolyte and the electrolytic products, and the advantages therefrom, is obtained by the construction shown in Figs. 4 and 5, it may not be possible in this construction to reduce the shunt current losses to the same extent as in the case of the construction shown in Figs. 1 to 3 inclusive.

In the structure shown in Figs. 4 and 5, as in the structure shown in Figs. 1, 2 and 3, that part of the electrolyte which is contained between the electrodes of the reacting couple, may circulate transversely and lengthwise of the reacting structures, and maintain a constant supply of fresh electrolyte in the zone of action, the strength of which may be regulated by the electrolyte fed into the cells from the intake headers during the cycle of action.

Having thus fully described the nature of our invention, what we claim as new and desire to secure by Letters Patent, is:—

1. An electrolytic apparatus comprising a cell, an electrode couple therein, an insulated offtake whose diameter bears such proportion to its length that the evolved gases during their ascent through said offtake convey with them portions of the electrolyte, gas separating means through which said evolved gases and portions of electrolyte are caused to circulate for their separation, and means for then returning the electrolyte to the cell.

2. An electrolytic apparatus comprising a cell, an electrode couple therein, an insulated offtake whose diameter bears such proportion to its length that the evolved gases during their ascent through said offtake convey with them portions of the electrolyte, temperature regulated gas separating means through which said evolved gases and portions of electrolyte are caused to circulate for their separation, and means for then returning the electrolyte to the cell.

3. An electrolytic apparatus comprising a cell, an electrode couple therein, an insulated offtake whose diameter bears such proportion to its length that the evolved gases during their ascent through said offtake convey with them portions of the electrolyte, gas separating means through which said evolved gases and portions of electrolyte are caused to circulate for their separation, and insulated means for then returning the electrolyte to the cell.

4. An electrolytic apparatus comprising a cell, an electrode couple therein, an insulated offtake for the top of the cell whose diameter bears such proportion to its length that the electrolyte may circulate with negligible shunt-current losses, and an intake for the bottom of the cell to complete the

cyclic movement of the electrolyte circulating through the offtake.

5. An electrolytic apparatus comprising a cell, an electrode couple therein, an insulated offtake for the cell whose diameter bears such proportion to its length that the electrolyte may circulate with negligible shunt-current losses, an intake for the cell to complete the cyclic movement of the elec-

trolyte, and means for regulating the temperature of the electrolyte returned from the offtake to the cell
